UNITED STATES PATENT OFFICE.

FRANZ GUILLEAUME, OF BONN, GERMANY.

DESIGN FOR A VASE OR SIMILAR ARTICLE.

SPECIFICATION forming part of Design No. 21,491, dated April 19, 1892.

Application filed March 22, 1892. Serial No. 425,998. Term of patent 3½ years.

To all whom it may concern:

Be it known that I, FRANZ GUILLEAUME, a subject of the Emperor of Germany, residing at Bonn, Rhenish Prussia, Germany, have invented certain new and useful Improvements in Designs for Vases and China-Ware; and I do declare the following to be a full, clear, and exact description of the invention, such as will enable others skilled in the art to which it appertains to make and use the same, reference being had to the accompanying drawing, and to the letters of reference marked thereon, which form a part of this specification.

The reference-letter *a* represents a Grecian vase or urn, to which the decorations described hereinafter are applied, and this vase is provided with a top *b*, having diametrically-opposite handles *c*, the latter extending down the sides of the vase. The upper end of each handle consists of a scroll *d*, provided with serrations *e*. The scroll is joined to the shoulder *f*. The lower part of the handle is made in the form of a leaf *g*, terminating in a scroll *h*, below which extends a succession of over-

lapping leaves *i*. On the sides of the vase between the handles is a bunch of cut flowers, the cut ends *j* of the stem *k* being located near the bottom of the base. The flowers consist of pansies having ragged edges. These are placed on a background of lilacs. Leaves branch out from the stem *k*, and other flowers are intermingled with the pansies. The entire bunch extends lengthwise of the vase, the tip of the bunch gracefully overlapping the point of juncture where the top of the vase joins the shoulders. The top of the vase is provided with a cap *l*, which is surmounted by a knob *m*.

What I claim as new, and desire to secure by Letters Patent, is—

The design for a vase or similar article, substantially as herein shown and described.

In testimony whereof I affix my signature in presence of two witnesses.

FRANZ GUILLEAUME.
